US00D793369S

(12) **United States Design Patent** (10) **Patent No.:** **US D793,369 S**
(45) **Date of Patent:** **** Aug. 1, 2017**

(54) **WIRELESS HEADSET**

(71) Applicant: **Shenzhen Qintong Technology Limited**, Shenzhen, Guangdong (CN)
(72) Inventor: **Shengling Zhou**, Guangdong (CN)
(73) Assignee: **Shenzhen Qintong Technology Limited**, Shenzhen (CN)

(**) Term: **15 Years**

(21) Appl. No.: **29/555,457**

(22) Filed: **Feb. 22, 2016**

(51) LOC (10) Cl. **14-01**
(52) U.S. Cl. **D14/223**

(58) **Field of Classification Search**

(57) **CLAIM**

The ornamental design for wireless headset, as shown and described.

DESCRIPTION

FIG. 1 is a front view of a wireless headset.

FIG. 2 is a rear view of the wireless headset of FIG. 1.

FIG. 3 is a left side view of the wireless headset of FIG. 1.

FIG. 4 is a right side view of the wireless headset of FIG. 1.

FIG. 5 is a bottom view of the wireless headset of FIG. 1.

FIG. 6 is a top view of the wireless headset of FIG. 1.

FIG. 7 is a perspective view of the wireless headset of FIG. 1.

FIG. 8 is a front view of a wireless headset.

FIG. 9 is a rear view of the wireless headset of FIG. 8.

FIG. 10 is a left side view of the wireless headset of FIG. 8.

FIG. 11 is a right side view of the wireless headset of FIG. 8.

FIG. 12 is a bottom view of the wireless headset of FIG. 8.

FIG. 13 is a top view of the wireless headset of FIG. 8; and,

FIG. 14 is a perspective view of the wireless headset of FIG. 8.
